UNITED STATES PATENT OFFICE

2,518,876

BASE FOR PRINTING PLATES AND A
METHOD FOR MANUFACTURING SAME

Max Fretz, Zurich, Switzerland

Application July 4, 1945, Serial No. 603,120
In Switzerland January 15, 1945

12 Claims. (Cl. 101—382)

1

Nowadays any half-tone plate used for printing is fitted on wood or lead blocks. In each case it is necessary to treat these blocks with a block leveller machine, in order to obtain the correct height. The wood blocks permitted the half-tone plates to be nailed, whilst on lead blocks they had to be mounted with glue foils or the like, or with glue.

Any plates nailed upon wood blocks have the advantage, that the first "make-ready" can be inserted between the plate and the block, but wood blocks have the disadvantage of warping. The lead blocks instead have the advantage to be absolutely level, but the disadvantage not to be able to insert the first "make-ready" between plate and block, since they are glued together.

Furthermore the pasting of the block requires a heating of the block and a subsequent pressing of the plate on the block. Heating is again required to remove the plate from the block.

The object of the present invention is to eliminate the above-said disadvantages, by casting a material adapted to be casted around inlaid pieces of nailable material. These inlaid pieces consist preferably of a material, whose coefficient of expansion is at least approximately the same as that of the material casted around them.

One preferred embodiment of the object of the present invention is represented schematically on the adjoining drawing.

The block 4 consists of a grate 3 composed of bars 1 and 2 of the same breadth, and with a height corresponding to the height of the block 4. The bars 1 and 2 have notches 6 equally spaced and can thus be set into each other at any distance, to build up a convenient grate. The material of the bars 1 and 2 will be preferably pear-wood, the texture being very dense and easily nailed. Lead is cast into this grate to the same height as the bars, building up a solid block of lead. A block leveller machine levels lead and wood at the same time. A block with a fine smooth surface of lead with wooden bars is therefore obtained. These blocks can be sawed to any size, without the block falling apart, due to the wooden frame in the block. As may be seen from the upper part of the drawing, the bars 1 and 2 reach partly to the surface of the block-mount. Between these visible parts, the bars disappear under the surface of the lead.

Instead of wood another kind of nailable material may be used, for instance, plastic material, whilst the lead or lead alloy may be substituted by some other metal or plastic mass.

Instead of a grate composed of crossing bars,

2

individual pieces of nailable material may be provided, which are cast into lead or into a lead alloy.

Instead of lead or lead alloy, other alloys with a low melting point may also be used.

What I claim and wish to secure by United States Letters Patent is:

1. A method for the manufacture of a base for printing plates comprising the steps of: assembling a plurality of bars of a nailable material crossing each other so as to form a grate having a plurality of empty spaces each of a configuration substantially in the shape of a parallelogram, each of said bars having a series of notches at at least one of its side edges, and pouring a castable material over said grate so as to fill in the empty spaces of said grate including such notches whereby a solid block of castable material having the main portions of said bars embedded therein is formed.

2. A method for the manufacture of a base for printing plates comprising the steps of: assembling a plurality of bars of a nailable material crossing each other so as to form a grate having a plurality of empty spaces each of a configuration substantially in the shape of a parallelogram, each of said bars having a series of notches at at least one of its side edges, pouring a castable material over said grate so as to fill in the empty spaces of said grate including such notches whereby a solid block of castable material having the main portions of said bars embedded therein is formed, and levelling the base in such a way that the surfaces of spaced portions of said bars under said notches are flush with at least one surface of said block.

3. A method for the manufacture of a base for printing plates comprising the steps of: assembling a plurality of bars of a nailable material crossing each other so as to form a grate having a plurality of empty spaces each of a configuration substantially in the shape of a parallelogram, each of said bars having a series of notches at its opposite side edges, and pouring a castable material over said grate so as to fill in the empty spaces of said grate including such notches whereby a solid block of castable material having the main portions of said bars embedded therein is formed.

4. A method for the manufacture of a base for printing plates comprising the steps of: assembling a plurality of bars of a nailable material crossing each other so as to form a grate having a plurality of empty spaces each of a configuration substantially in the shape of a parallelogram, each of said bars having a series of notches at its

opposite side edges, pouring a castable material over said grate so as to fill in the empty spaces of said grate including such notches whereby a solid block of castable material having the main portions of said bars embedded therein is formed, and levelling the base in such a way that the surfaces of spaced portions of said bars between said notches are flush with opposite surfaces of said block.

5. A method for the manufacture of a base for printing plates comprising the steps of: assembling a plurality of bars of a nailable material crossing each other and having a series of notches at its opposite side edges by engaging predetermined notches of said bars with each other in a manner so as to form a grate having a plurality of empty spaces each of a configuration substantially in the shape of a parallelogram, and pouring a castable material over said grate so as to fill in the empty spaces of said grate including such notches whereby a solid block of castable material having the main portions of said bars embedded therein is formed.

6. A method for the manufacture of a base for printing plates comprising the steps of: assembling a plurality of bars of a nailable material crossing each other and having a series of notches at its opposite side edges by engaging predetermined notches of said bars with each other in a manner so as to form a grate having a plurality of empty spaces each of a configuration substantially in the shape of a parallelogram, pouring a castable material over said grate so as to fill in the empty spaces of said grate including such notches whereby a solid block of castable material having the main portions of said bars embedded therein is formed, and levelling the base in such a way that the surfaces of spaced portions of said bars between said notches are flush with opposite surfaces of said block.

7. A base for printing plates comprising: a grate made of a plurality of bars of nailable material connected with each other, each of said bars having a series of notches at at least one of its side edges, and a solid block of a cast material arranged in the empty spaces of said grate including such notches, the main portions of said bars being embedded in said solid block.

8. A base for printing plates comprising: a grate made of a plurality of bars of nailable material connected with each other, each of said bars having a series of notches at at least one of its side edges, and a solid block of a cast material arranged in the empty spaces of said grate including such notches, the main portions of said bars being embedded in said solid block, and the surfaces of spaced portions of the side edges of said bars between said notches being flush with at least one surface of said block.

9. A base for printing plates comprising: a

grate made of a plurality of bars of nailable material connected with each other, each of said bars having a series of notches at its opposite side edges, and a solid block of a cast material arranged in the empty spaces of said grate including such notches, the main portions of said bars being embedded in said solid block.

10. A base for printing plates comprising: a grate made of a plurality of bars of nailable material connected with each other, each of said bars having a series of notches at its opposite side edges, and a solid block of a cast material arranged in the empty spaces of said grate including such notches, the main portions of said bars being embedded in said solid block, and the surfaces of spaced portions of the side edges of said bars between said notches being flush with opposite surfaces of said block.

11. A base for printing plates comprising: a grate made of a plurality of bars of nailable material, each of said bars having a series of notches at its opposite side edges, said bars being connected with each other by the engagement of predetermined notches with each other, and a solid block of a cast material arranged in the empty spaces of said grate including such notches, the main portions of said bars being embedded in said solid block.

12. A base for printing plates comprising: a grate made of a plurality of bars of nailable material, each of said bars having a series of notches at its opposite side edges, said bars being connected with each other by the engagement of predetermined notches with each other, and a solid block of cast material arranged in the empty spaces of said grate including such notches, the main portions of said bars being embedded in said solid block, and the surfaces of spaced portions of the side edges of said bars between said notches being flush with opposite surfaces of said block.

MAX FRETZ.
